United States Patent Office

Des. 188,795
Patented Sept. 13, 1960

188,795

AUTOMATIC TELEPHONE RECORDING APPARATUS

Kenneth A. Catto, Beaverton, Oreg., assignor to Code-A-Phone Electronics, Inc., Seattle, Wash., a corporation of Washington

Filed Sept. 14, 1959, Ser. No. 57,553

Term of patent 14 years

(Cl. D26—14)

Fig. 2.

Fig. 1.

Fig. 1 is a front perspective view of an automatic telephone recording apparatus, showing my new design; and

Fig. 2 is a rear perspective view thereof.

The cross hatched areas on the top and side surfaces in the figures are representative of a woven fabric pattern covering the entire top and side surfaces in both figures, between the rear and front panels.

I claim:

The ornamental design for an automatic telephone recording apparatus, as shown and described.
